ERIC PERCIVAL MUNTZ, OF HAMILTON, ONTARIO, CANADA

CLAMP FOR WIRE, RODS, AND THE LIKE

Application filed June 7, 1932. Serial No. 615,941.

My invention relates to improvements in clamps, for wire, rods and the like, and has been more particularly developed for use in the tying of concrete form work. The object of my invention is to provide a clamp which is of compact form and which can be readily attached and released, and a further and particular object of my invention is to furnish a cage element within the clamp 5 and for retaining the chuck jaws in alignment so that the clamping action of such jaws upon the wire is always evenly distributed.

A still further object of my invention is to utilize the jaw locking element which protrudes from the clamp as the means whereby the clamp is secured to the form work and drawn up to tauten the wire or rod to which it is attached, and my invention also includes, in an alternative form, 15 the provision of a resilient element within the clamp which acts upon the clamp jaws so that they exercise their gripping function when the clamp is initially positioned upon the tie wire or rod, such resilient pressure being afterwards made positive by a manual jaw locking element.

My invention consists of a clamp for wire, rods and the like, all as hereinafter more particularly described and illustrated in the accompanying drawing, in which:—

Fig. 1 is a vertical cross sectional view through my clamp.

Fig. 2 is a vertical transverse sectional view taken through the line 2—2 of Fig. 1.

Fig. 3 is a vertical transverse sectional view taken through the line 3—3 Fig. 1.

Fig. 4 is a perspective view of the cage 40 in which the chuck jaws are contained.

Fig. 5 is a perspective view of one of the chuck jaws.

Fig. 6 is a similar view to Fig. 1 showing my alternative construction incorporating 45 the resilient element, and

Fig. 7 is a cross sectional view through a fragmentary portion of concrete form work showing my clamp as it is positioned when in use.

50 Like characters of reference indicate cor-

responding parts in the different views in the drawing.

My invention has been particularly evolved to permit the use of hard steel wire of great strength for the tying of concrete 55 form work and for similar purposes. This wire, which is of high carbon steel, has a very great strength as compared to annealed wire and is now a commercial product. While this wire is greatly superior to 60 annealed wire for the tying of concrete form work, it heretofore has not been possible to use this wire as, of course, it is not susceptible to being readily bent for tying as is the case with annealed wire, and as 65 tying in concrete work forms a large item in the labour and material costs incidental to the construction of forms, I have evolved my clamp whereby this hard steel wire may be used and I have so designed my clamp 70 that the ultimate strength of the wire is not appreciably decreased at the clamping point.

My clamp, as illustrated in Fig. 1 of the drawing, comprises a housing 1 which is of cylindrical form and internally threaded. 75 The housing 1 contains a jaw socket 2 which is threaded thereinto intermediately of its length. The inner jaw receiving portion of the socket is of truncated conical form and its inner end, which is of less diameter, is 80 furnished with a central orifice 3 through which the rod or wire passes. Abutting the end of the socket containing the orifice 3, I furnish a plug 4 having a bore 5 therethrough which forms a continuation of the 85 orifice 3. The plug is threaded into the housing 1 and formed upon its outer face with a squared spanner receiving portion 6 by means of which the clamp is held against rotation as shall be hereinafter explained. 90

The jaw containing cage as illustrated in Fig. 4, is adapted to be positioned within the jaw socket and comprises an upper ring 7 and a lower ring 8 connected together by a pair of diametrically opposed struts 9, 95 the diameters of the rings 7 and 8 being substantially in the same ratio as the diameters of the inner and outer ends of the pair of chuck jaws 10 which are seated between the rings 7 and 8 and adapted to 100

- move together or apart dependent upon the direction in which they are moved within the cup, in accordance with standard chuck construction. The provision of the cage in 5 no way interferes with the radial movement of the chuck jaws 10 but retains such chuck jaws in transverse alignment so that they, at all times, exert an equal gripping pressure upon the contained wire or rod. The inner 10 wire engaging faces 11 of the chucks are each formed with a central longitudinal groove 12 which is suitably serrated to furnish a non-slipping grip upon the wire.
- The open end of the housing 1 is adapted 15 to receive the end of a wale bolt 13 which is threaded thereinto to bear against the ring 8 of the chuck cage so that inward movement of the wale bolt against the cage has a tendency to move the cage forwardly into 20 the socket thus pressing the jaws towards each other. The wale bolt 13, which is formed with a central bore 14, is furnished with a pair of lock nuts 15 and 16 upon its outer end.
- 25 In the alternative form shown in Fig. 6, I follow the same principles of construction as in the clamp illustrated in Fig. 1 with the exception that in this form I provide a wale bolt engaging element 17 which is attached to the ring 8 of the cage. The element 17, which is slidable within the housing 1, has a stud receiving slot 18 extending thereacross for the reception of a stud 19 extending from the end of the wale bolt 20 30 which is threaded through a plug 21 in the end of the housing 1. The stud 19 is formed with a head 22 which is movable within the slot 18 but cannot be longitudinally withdrawn therefrom through the provision of the slot shoulders 23. A compression spring 24 is furnished between the element 17 and the plug 21 so that the cage and jaws always have a tendency to move into the socket. In this construction, as shown in Fig. 35 40 45 6, I do not show the plug 4 in the other end of the housing 1 but furnish a hexagon or squared spanner receiving portion 25 upon the outer face of the housing 1.
- The operation of my device is as follows: 50 When inserting the tie wire end in my clamp as illustrated in Fig. 1, I unthread the wale bolt 13 so that it permits the jaw containing cage a movement out of the cup whereby the jaws are permitted an opening 55 movement. The end of the wire 26 is then inserted into the clamp through the bore 5 and orifice 3 and as it passes into and through the cage the jaws are moved apart and merely rest upon the wire. If the wire is 60 comparatively long it will pass from the chuck jaws into the bore 14 of the wale bolt. The clamp is slid along the wire until the desired position is reached and the wale bolt 13 is then threaded inwardly in the 65 housing 1 to bear against the ring 8 of the
- jaw cage thus forcing the cage into the jaw socket and the jaws into tight wedging engagement between the walls of the jaw socket and the wire upon which they are clamping. In performing this operation the 70 lock nuts 15 and 16 are threaded together upon the wale bolt so that they can be utilized for rotating the wale bolt and the clamp is held against rotation by the use of a spanner upon the squared end 6. When it is desired to remove the clamp or readjust it upon the wire, the wale bolt is unthreaded from out of contact with the ring 8 thus taking the pressure from off the jaws.
- In the type of clamp illustrated in Fig. 6, 80 the wale bolt 20 is threaded from out of the housing 1 to take pressure from off the jaw cage and the wire is inserted through the orifice 3, it being understood that the wale bolt 20 is also formed with a bore 27 for the reception of the wire 26 if so desired. It will be generally found that the pressure of inserting the wire against the jaws will be sufficient to move them rearwardly 85 against the spring 24 whereby they can move sufficiently far apart for the easy insertion of the wire, but in cases where there is any difficulty in overcoming resilient action of the spring the wale bolt 21 is threaded from out of the clamp a sufficient distance so that the head 22 upon the stud 19 engages the shoulders 23 of the element 17 thus drawing the element 17 and jaw cage away from the jaw cup. When the wire has been inserted 90 and is contained between the jaws the clamp is slid along the wire until the desired position is reached and it will be found that immediately there is any tendency to pull the wire from out of the clamp or slide the clamp backwards on the wire that the movement of the chuck jaws within the tapered socket under the spring 24 will be sufficient to retain the wire and clamp against disengaging movement relatively to each other.
- 95 When the clamp is finally positioned in its adjusted position to the wire the wale bolt 20 is threaded inwardly so that its end bears against its element 17, thus moving the jaw cage into the socket and tightly wedging the jaws upon the wire. When it 100 is desired to remove the clamp or re-adjust it upon the wire the wale bolt 20 is loosened from out of contact with the element 17 which will, in most cases, permit the jaws to loosen upon the wire. If the jaws do not readily loosen the wale bolt 20 is threaded outwardly a further degree until the stud head 22 engaging the shoulders 23 draws the cage loose in the socket.
- 105 In Fig. 7 of the drawing, I show my 110 clamp as it is used in tying concrete form work wherein 28 is one panel of the form, 29 the stud and 30 a pair of wales. The tie wire 26 extends from the panel at one side 115 of the form and projects through an orifice 120

32 in the panel 28 at the other side of the form, such projecting portion being gripped with my clamp which, in turn, has its wale bolt 13 extending between the wakers 30 and 5 provided with a washer or draw plate 33 through which it extends and against which the nut 15 bears to exert a pull upon the clamp and draw the wire 26 taut. In this manner the form panels are retained in their 10 predetermined relation.

My invention, as hereinbefore described, provides for the use of the wale bolt to positively lock the jaws upon the wire and thus prevent a forward slip of the clamp 15 should the load be temporarily released and the wire shoved back in relation to the panel of the form adjacent the clamp. This feature is very necessary for accurately holding 20 form work to line during construction, for if the form should tend to move in any place the concrete when placed against it will move it out until the restraining wire tie and clamp takes the strain. It will thus be understood that if the clamp should inadvertently slip forwardly upon the wire when 25 the strain was released, that the tie would be shortened and hold its form out of alignment. The type of wire for which my clamp has been evolved is particularly desirable 30 for concrete form work in that it is moderate in price and has a relatively large strength for a small diameter i. e. high carbon steel wire having a diameter of 0.187 inches has an ultimate strength of 5600 35 pounds and furthermore, as the diameter of the wire is comparatively small as compared to threaded rods which have been in some cases used as the tying means for concrete forms, it is only necessary to furnish very 40 small holes in the form panel for the reception of my tie wires, and this of course eliminates excessive mutilation of the panels and thus permits them a much longer life than is ordinarily the case. In fact where 45 steel panels are used they can be provided with a number of differently positioned holes for the reception of my tie wires in any relation or position that may be required, the holes that do not contain wires being 50 so small that they are of no detriment and do not have to be filled.

While I have described my clamp as particularly designed for use in conjunction with hard wire for the tying of concrete 55 forms, it is to be understood that it has many other uses and can be used for scaffolding work of any kind where wires may be suspended for supporting platforms and also for holding guy wires, for cold drawing 60 of wire or rods or for picking up packages or bundles bound with wire and having the free end of the binding wire exposed to which the clamp can be attached and in fact for many other uses.

65 Although I have shown and described a

particular embodiment of my invention it is to be understood that it is susceptible to any changes and alterations which I may, at any time, deem necessary without departing from the spirit of my invention as set forth 70 in the appended claims.

What I claim as my invention is:

1. In a retaining clamp of the character described comprising a casing having a socket therein of truncated conical interior 75 and open at both ends, a plurality of chuck jaws slidably contained within the socket, a pair of ring members positioned at the ends of the jaws, strut pieces extending from ring to ring between the jaws, and a threaded jaw moving rod screwed into the casing 80 concentrically with the socket for retaining the jaws in any set clamping position.

2. In a retaining clamp of the character described comprising a casing having a 85 socket therein of truncated conical interior and open at both ends, a plurality of chuck jaws slidably contained within the socket, a pair of ring members positioned at the ends of the jaws, strut pieces extending from ring to ring between the jaws, and manually 90 adjustable means protruding from the housing for retaining the jaws in any set clamping position.

3. In a retaining clamp of the character 95 described comprising a casing having a socket therein of truncated conical interior and open at both ends, a plurality of chuck jaws slidably contained within the socket, a ring member movably contained within 100 the socket and against which the end faces of the jaws are seated, means extending from the ring between the jaws for retaining the jaws against movement relatively to the ring, and manually actuatable means movable within the casing and bearing against the ring.

4. In a retaining clamp of the character described comprising a casing having a 110 socket therein of truncated conical interior and open at both ends, a plurality of chuck jaws slidably contained within the socket, a pair of ring members positioned at the ends of the jaws, strut pieces extending from ring to ring between the jaws, and 115 manually actuatable means movable within the casing and bearing against one ring.

5. In a retaining clamp of the character described, the combination with a plurality of slidable chuck jaws contained within a 120 socket in a housing, said socket having a sloping wall and open at both ends and a sliding jaw containing element contained within the housing, of a compression spring interposed between one end of the housing 125 and the element, and a rod adjustably threaded into and protruding from the housing and adjustably exerting a pressure against the sliding element.

6. In a retaining clamp of the character 130

described, the combination with a plurality of slidable chuck jaws contained within a socket in a housing, said socket having a sloping wall and open at both ends and a
5 sliding jaw containing element contained within the housing, of a compression spring interposed between one end of the housing and the element, and a rod manually movable into and out of the housing and coupled
10 to the jaw containing element.

7. In a retaining clamp of the character described comprising a casing having a socket therein of truncated conical interior and open at both ends, a plurality of chuck
15 jaws slidably contained within the socket, a pair of ring members positioned at the ends of the jaws, strut pieces extending from ring to ring exteriorally of the jaws, and manually adjustable means protruding from
20 the housing for retaining the jaws in any set clamping position.
